UNITED STATES PATENT OFFICE.

THOMAS J. JOHNSON AND JOHN C. LUCAS, OF ALLENWOOD, PENNSYLVANIA.

TRACE-HITCH.

1,051,115.

Specification of Letters Patent. Patented Jan. 21, 1913.

Application filed May 7, 1912. Serial No. 695,675.

To all whom it may concern:

Be it known that we, THOMAS J. JOHNSON and JOHN C. LUCAS, both citizens of the United States, and residents of Allenwood, 5 in the county of Union and State of Pennsylvania, have invented a new and Improved Trace-Hitch, of which the following is a full, clear, and exact description.

Among the principal objects which the 10 present invention has in view are: to provide a device of the character named, adjustable to accommodate traces of various thicknesses; to increase the range of adjustment of the length of the traces; and to facilitate 15 the operation of fastening the traces in operative position.

Reference is to be had to the accompanying drawings forming a part of this specification, in which similar characters of reference 20 indicate corresponding parts in all the views, and in which—

Figure 1 is a side elevation of an end fragment of a swingletree provided with a hitching device constructed and arranged 25 in accordance with the present invention; Fig. 2 is a top plan view of the same; and Fig. 3 is a detail view in vertical section taken on the line 3—3 in Fig. 2, showing the movable member of the clamping plates.

As seen in the accompanying drawings, 30 the swingletree A has fastened thereon an end ferrule 8, formed integral with, and at the inner side of, a clamping plate 9. The clamping plate 9 and ferrule 8 are in-

tegrally formed with an anchoring strip 10, 35 which extends lengthwise of the swingletree A, and is at the end provided with curved tabs 11, to form a seat to encompass the swingletree A. The strip 10 is suitably per-

forated to receive any suitable fastening 40 devices, such as nails 12. The end of the strip 10 at the outer side of the plate 9, is spread to accommodate the formation therein of a longitudinally-disposed slot 13. The slot

45 13 is provided to receive a stud 14, extended from a movable clamping plate 15. The end of the stud 14 is extended through a washer 16 at the under side of the strip 10, and is then headed to hold said washer

50 firmly in position. This construction is seen best in Fig. 3 of drawings. To guide the plate 15 in its movement on the strip 10, and to facilitate the formation of the stud 14, the body of the plate 15 is recessed 55 at each side of the stud 14, said recesses being shaped to receive the sides of the strip

10, to be used as a guide for the movement of the plate 15.

The plate 15 is moved to and from the trace B, partly by hand, and partly by 60 means of a lever 17. The movement by hand is that which adjusts the plate 15, to rest lightly against the outer side of the trace B. The pressure which is imposed upon the plate 15 is thereafter produced by 65 a cam spur 18, with which the lever 17 is provided. The lever 17 is furnished with trunnions 19, which form a bearing in perforations provided in the end post 20 formed integral with the strip 10 and perpendicularly 70 extended therefrom at the end of the hitching device. The spur 18 is shortened, to be introduced at the back of the plate 15 when the latter is lightly pressed against the trace B of maximum thickness for which the 75 hitching device is designed. The width or base of said spur 18 is of sufficient length to move the plate 15 to firmly grip the trace of the least thickness for which the hitch is designed. In the position of the hitch where 80 the trace B is gripped, the lever 17, as seen in full lines in Fig. 1, is prone upon the swingletree A, and is in service held in this position by means of a bridle 21. The bridle 21 is pivotally mounted upon studs 22 85 projected from the edges of the strips 10. The disposition of the studs 22 is such that the bridle 21, when swung to release the lever 17, rests upon the swingletree beyond 90 the end of the lever 17.

The operation of a device thus constructed is as follows:—The trace B is drawn upon, to take up the slack in the trace, and is then laid edgewise between the plates 9 and 15. It will be noted that said plates are 95 curved horizontally, and that the adjacent faces of said plates are vertically ribbed, serrated, or corrugated. The plate 15 is then moved by hand, to lightly rest against the outer side of the trace, and the lever 17 100 is thrown over on its pivot, the short end of the spur 18 passing behind the plate 15, until the surface of the spur rests lightly on the upper edge and outer face of the plate 15. From this point until the lever 17 is 105 depressed upon the swingletree A, the increased dimension or cam-like shape of the spur 18 operates to jam or crowd the plate 15 forward against the trace B, and to sink the serrations of both plates into the material of the trace, to firmly grip the same. 110 In this position, the bridle 21 is drawn over

the free end of the lever 17, to rest upon, and be engaged by, one of the teeth 23 formed adjacent the free end of the lever 17.

It will be understood that in the above 5 operation, should the trace B have a thickness which would prevent the full deposition of the lever upon the swingletree A, the movement of the bridle 21 would accommodate the variation in said movement of 10 the lever 17, the engagement between the bridle and lever having sufficient latitude to accommodate the variation in extent of movement referred to.

When it is desired to release the trace 15 from engagement with the hitch, the lever 17 is slightly depressed or swung downward to release the engagement of the teeth 23 thereof with the bridle 21, when the bridle 21 is moved over the free end of the lever 17 20 to disengage the same. The lever 17 is then drawn to a full released position, such as shown in dotted lines in Fig. 1 of the drawings, when the plate 15 may be retracted, and the trace B lifted from engagement with 25 the plates 9 and 15.

It will be seen that the construction is such as would accommodate traces having a great variety in their thickness, and that the length of the trace to suit the service conditions thereof is nicely accommodated. It 30 will also be seen that with a trace hitch of the character described, and shown in the accompanying drawings, the trace is not weakened by the formation therein of per- 35 forations to receive and hold a buckle tongue, as is the usual practice.

Having thus described our invention, we claim as new and desire to secure by Letters Patent:

40 1. A trace hitch, comprising a clamping plate adapted to be fixedly mounted on a swingletree, and having a ferrule to receive the end of said swingletree; and an anchoring strip for securing the hitch to said tree; 45 a lever having a cam-shaped spur and pivotally mounted on said anchoring strip, at the outer side of said clamping plate; and a second clamping plate slidably mounted on said anchoring strip, between the pivot of 50 said lever and said first-mentioned clamping plate.

55 2. A trace hitch, comprising a clamping plate adapted to be fixedly mounted on a

swingletree, and having a ferrule to receive the end of said swingletree and an anchoring strip for securing said hitch to said tree; 55 a lever having a cam-shaped spur and pivotally mounted on said anchoring strip, at the outer side of said clamping plate; a second clamping plate slidably mounted on said anchoring strip, between the pivot of 60 said lever and said first-mentioned clamping plate; and a swinging bridle pivotally mounted on said anchoring strip to engage the free end of said lever when in service position. 65

3. A trace hitch, comprising a clamping plate adapted to be fixedly mounted on a swingletree, and having a ferrule to receive the end of said swingletree and an anchoring strip for securing said hitch to said tree; 70 a lever having a cam-shaped spur and pivotally mounted on said anchoring strip, at the outer side of said clamping plate; and a second clamping plate slidably mounted on 75 said anchoring strip between the pivot of said lever and said first-mentioned clamping plate, said clamping plates being curved longitudinally and in line with the trace held between said plates in service position. 80

4. A trace hitch, comprising a clamping plate adapted to be fixedly mounted on a swingletree, and having a ferrule to receive the end of said swingletree, and an anchoring strip for securing said hitch to said tree; 85 a lever having a cam-shaped spur and pivotally mounted on said anchoring strip, at the outer side of said clamping plate; a second clamping plate slidably mounted on said anchoring strip, between the pivot of said 90 lever and said first-mentioned clamping plate; and a swinging bridle pivotally mounted on said anchoring strip to engage the free end of said lever when in service position, the upper surface of said lever being provided with teeth to engage said 95 bridle.

In testimony whereof we have signed our names to this specification in the presence of two subscribing witnesses.

THOMAS J. JOHNSON.
JOHN C. LUCAS.
